United States Patent Office.

JOEL HAINES, OF WEST MIDDLEBURG, OHIO.

Letters Patent No. 100,396, dated March 1, 1870.

IMPROVEMENT IN FRUIT-JARS.

The Schedule referred to in these Letters Patent and making part of the same.

To all whom it may concern:

Be it known that I, JOEL HAINES, of West Middleburg, Logan county, in the State of Ohio, have invented certain new and useful Improvements in Fruit-Jars; and I hereby declare the following to be a full and exact description thereof, reference being had to the accompanying drawing forming part of this specification.

The nature or essence of my invention consists in certain improved features, (to be fully described below,) in a combination of devices for closing air-tight the top or mouth of a glass or other jar.

In the drawing hereinbefore mentioned—

Figure 1 is a top view of a jar with the cover off.

Figure 2 is a vertical section through the center of the top of the jar and the cover.

Figure 3 shows the usual spring-clasp for holding the cover down.

At the mouth of the jar A the top surface b is creased or corrugated so as to make circular ridges or depressions, or both, upon it, in order that the more prominent parts may be pressed into the yielding surface of the packing or gasket d placed upon it, and thus form an air-tight joint beneath the packing with less pressure than would otherwise be required.

For the same purpose a single edge of the tin (or other sheet metal) cover e is made to project downward so as to meet the top surface of the gasket or packing d, and this edge being easily pressed into the said packing an air-tight joint is thus formed above the packing by a very light pressure on the lid or cover.

The two inclines i, up which on either side the clasp H is pushed to press down and hold the lid, are formed of tin or other sheet-metal, and so arranged that the top is a single cut or raw edge of the metal, which, by friction and by the slight indentation made, causes the clasp to stick more securely where it is placed in closing the jar.

The foregoing being a description of my improvements in fruit-jars or cans,

What I claim, and desire to secure by Letters Patent, is—

The combination of the creased or corrugated surface b, the yielding packing d, and the single edge of sheet-metal projecting downward from the cover to meet the packing, substantially as described.

JOEL HAINES.
